United States Patent Office

Des. 211,928

Patented Aug. 13, 1968

211,928

BOTTLE

Robert R. Burnett, Webster, N.Y., assignor to Xerox Corporation, Rochester, N.Y., a corporation of New York

Filed Dec. 2, 1966, Ser. No. 4,897
Term of patent 14 years

(Cl. D9—44)

FIG. 1

FIG. 2

FIG. 4

FIG. 3

FIG. 1 is a front perspective view of a bottle showing my new design;

I claim:

The ornamental design for a bottle, as shown.
